UNITED STATES PATENT OFFICE.

EDWIN J. GRANT, OF GUILFORD, MAINE.

AUTOMATIC OIL-CUP.

No. 893,482.

Specification of Letters Patent.

Patented July 14, 1908.

Application filed October 29, 1907. Serial No. 399,677.

To all whom it may concern:

Be it known that I, EDWIN J. GRANT, a citizen of the United States, residing at Guilford, in the county of Piscataquis and State of Maine, have invented new and useful Improvements in Automatic Oil-Cups, of which the following is a specification.

This invention is an improved oil cup and thermostatic means for controlling the discharge of oil or other lubricant therefrom, the object being to provide an automatic oil cup which will increase the supply of lubricant to a bearing which becomes heated so as to prevent overheating of said bearing, and said invention consists in the construction, combination and arrangement of devices hereinafter described and claimed.

In the accompanying drawings: Figure 1 is a sectional view of an oil cup constructed in accordance with this invention. Fig. 2 is a plan of the same. Fig. 3 is horizontal sectional view of the same on plane indicated by line *a—a* of Fig. 1.

The oil cup is here shown as comprising a base 1, a cap 2 and a body 3. The base and cap are preferably made of metal. The base particularly should be made of brass or other metal which is a good conductor of heat. Said base and cap are provided on their opposite sides with circular flanges 4, 5, respectively, the flange 5 of the cap being internally screw-threaded. The body 3 is a hollow cylinder, preferably of glass, however, and open at its upper and lower ends with its lower end secured in a circular seat 6 in the upper side of the base and its upper end provided with screw threads engaging those of the cap 2 so that the cap may be readily detached from the body of the cup and reattached thereto as may be required.

The base is provided with the usual depending threaded stem 7, whereby it may be readily secured to a bearing or detached therefrom. The oil feeding duct 8 extends through the base and through the stem thereof as shown. The boss 9 is formed on the upper side of the base around the upper end of the duct 8 and is provided with an inverted frusto-conical seat 10, for a similarly shaped oil regulating valve 11. The said base is further provided with a transverse sight bore 12, which intersects the duct 8 and is provided at its ends with transparent closures 13, preferably made of glass, said sight bore enabling the passage of the oil through the duct to be observed. The

tube 14, which has its upper end open, and its lower end closed, also has its lower end secured in a socket 15, in the base 1 at a point in the center thereof. A column of mercury 16 is in the lower portion of the said tube.

The cap 2 is constructed with a pair of standards 17, which rise from its upper side, and which support a bridge piece 18, said standards terminating at their upper ends in screws 19, which pass through openings in the bridge piece, nuts 20 being provided to engage said screws and bear on said bridge piece to secure the latter firmly on the upper end of the standards, and yet allowing the bridge piece to be readily detached from the standards. The valve 11 is provided with a rod 21, which extends upwardly through and is guided in the openings in the cap 2 and in the bridge piece. The upper end of the said valve rod is similarly threaded and is provided with an adjusting nut 22, which bears on the bridge piece. The said valve rod is provided at a point above the cap 2 with a stop 23, which is here shown as a disk. A coiled extensible spring 24 is placed on the said valve rod and bears between the bridge piece and the said stop, thereby serving to keep the valve rod and hence also the valve normally depressed so that the valve normally closes to prevent the passage of lubricant from the cup through the duct to the bearing. In order to set the valve at work to control the passage of lubricant through the duct, said valve must be adjusted to the required extent by means of the nut 22.

The piston 25 is fitted snugly in the tube 14, to rise with the expansion of the column of mercury, and the said piston has a rod 26 which extends through and is guided by openings in the cap 2 and the bridge piece 18. Said piston rod is provided at a point above the cap with a stop 28, which is here shown as a disk one side of which bears under and engages one side of the stop 23 of the valve rod 21. A coiled extensible spring 29 which is on the piston rod 26 bears between the bridge piece and the stop 28 and serves to normally depress the piston.

In the operation of my improved oil cup after the valve has been adjusted by the nut 22 the oil is permitted to pass by gravity drop by drop through the duct, and the sight bore enables the operator to readily adjust the valve and cause a suitable quantity of lubricant to be supplied to the bearing.

In the event that the valve is so adjusted that an insufficient quantity of lubricant is fed to the bearing and the latter becomes heated, the heat of the bearing is communicated to the base 1, which, as before stated, is a good conductor of heat, so that the column of mercury in the tube 14 is caused to expand. Such expansion of the column of mercury in the tube causes the piston 25 to rise against the tension of the spring 29 and the stop 28 of the piston rod, by reason of its engagement with the stop 23 of the valve rod, causes the valve to be also raised so that an increased quantity of oil is caused to flow through the duct to the bearing. As the bearing cools the column of mercury contracts, the spring 29 causes the piston to be lowered, and the spring 24 causes the valve rod and hence the valve also to be lowered until the valve regains the position in which it was set by the adjustment of the nut 22.

I do not desire to limit myself to the precise construction combination, and arrangement of devices herein described and shown, as it is evident that modifications may be made therein within the scope of the appended claims.

Having thus described my invention, what I claim as new and desire to secure by Letters Patent, is:

1. An automatic oil cup comprising a base and having an oil feed duct and a valve seat at the upper end of said duct, a body on said base, a cap on said body and having standards, a tube in the body, rising from the base and having a column of material expansible by heat, a piston in said tube on said column and having an upwardly extending rod operating in an opening in the cap, said rod having a stop above the cap, a valve to coact with the valve seat to open and close the oil feed duct, said valve having an upwardly extending rod operating in an opening in the oil cup, said rod having a stop above that of

the piston rod and adapted to come in contact therewith, a bridge-piece connecting the standards and forming a guide for the valve rod and piston rod, a spring to depress the valve, a nut on said valve rod to adjust said valve and a spring to depress the piston. 45

2. An automatic oil cup having a thermostatically-acting device and a valve operated in one direction by and adjustable independently of the thermostatically-acting device. 50

3. An automatic oil cup comprising a base 55 having an oil feed duct, a body on the base, a cap on and removable from the body, thermostatically-acting means having an element on the base and in the body and including a movable element having a rod provided 60 with a stop, a valve to open and close the oil feed duct and having a rod provided with a stop, said rods extending through and being guided by openings in the cap, and said stops coacting to cause the valve to move with the 65 movable element of the thermostatically acting means.

4. An automatic oil cup comprising a base 70 having an oil feed duct, a body on the base, a cap on and removable from the body, thermostatically-acting means having an element on the base and in the body and including a movable element having a rod provided 75 with a stop, a valve to open and close the oil feed duct and having a rod provided with a stop, said rods extending through and being guided by openings in the cap and said stops coacting to cause the valve to move in one 80 direction with the movable element of the thermostatically acting means, and springs to normally move the valve and piston to initial position.

In testimony whereof I affix my signature in presence of two witnesses.

EDWIN J. GRANT.
